UNITED STATES PATENT OFFICE.

JAMES MACDONALD, OF NEW YORK, N. Y.

BILL-BOOK.

1,267,246.

Specification of Letters Patent. Patented May 21, 1918.

Application filed August 22, 1917. Serial No. 187,607.

To all whom it may concern:

Be it known that I, JAMES MACDONALD, a citizen of the Dominion of Canada, and a resident of the city of New York, borough 5 of Manhattan, in the county and State of New York, have invented a new and Improved Bill-Book, of which the following is a full, clear, and exact description.

The invention relates to pocket books and 10 its object is to provide a new and improved bill book arranged to securely hold and readily accommodate a large number of bank bills and other valuable papers in folded position and without producing an 15 unduly bulky package. Another object is to permit the user to readily open the bill fold for convenient insertion or removal of the bills.

In order to accomplish the desired result 20 use is made of a flexible back approximately of the size of a bill, side pieces overlying the side portions of the said back and connected thereto along the outer and bottom edges, and a closing flap connected at the middle 25 portion of its bottom edge with the corresponding portion of the bottom edge of the said back, the ends of the connected middle portion of the said front flap being spaced from the adjacent inner edges of the said 30 side pieces, the free end portions of the said front flap being adapted to be tucked under the said side pieces, the latter being adapted to be folded one on the other, the innermost 35 overlying the middle portion of the said front flap.

A practical embodiment of the invention is represented in the accompanying drawings forming a part of this specification, in which similar characters of reference indicate corresponding parts in all the views.

Figure 1 is a perspective view of the bill book in a partly open position and with a portion of one of the side pieces broken out;

Fig. 2 is a similar view of the same completely open for the insertion or removal of bills;

Fig. 3 is an edge view of the same with the parts in folded position; and

Fig. 4 is a sectional plan view of a portion of the bill book on the line 4-4 of Fig. 1.

The back 10 of the bill book is made of leather or other suitable flexible material and approximately of a size corresponding 55 to that of an ordinary bill. The side portions of the back 10 are overlaid by similar

flexible side pieces 11 and 12 connected along the outer and bottom edges to the corresponding edges of the back 10 by stitches 13 and 14, as plainly indicated in the drawings. 60 A front flap 15 of a flexible material has a connection 16 at the middle portion of its bottom with a corresponding middle portion of the bottom of the back 10. The front flap 15 has extended side portions 17 and 18 adapted to be tucked under the side pieces 11 and 12 to securely hold the bills or other papers in position between the back 10 and the front flap 15 and its extended portions 17 and 18. The front flap 15 is preferably integrally connected with the back 10 at the connection 16 but the back 10 and the front flap 15 may be made of two pieces fastened together at 16. The ends of the connection 16 are spaced from the adjacent 75 inner edges of the side pieces 11 and 12 to provide readily foldable compact portions 19 and 20 to permit convenient folding of the side portions of the bill book one upon the other, with the innermost side portion 80 overlying the middle portion of the front flap 15, as plainly indicated in Fig. 3.

In order to hold the end pieces 17 and 18 of the front flap 15 from accidentally sliding out when tucked under the side pieces 85 11 and 12, use is made of loops 21, one for each side piece 11 or 12, and arranged at the inner face thereof with the top and bottom edges fastened to the corresponding top and bottom edges of the side pieces 11 and 12. The end pieces 17 and 18 are provided with retaining lips 22 adapted to abut against the inner edges of the loops 21 to prevent the end pieces 17 and 18 from coming out from under the side pieces 11 and 12. The outer faces of the side pieces 11 and 12 are preferably provided with card cases 25, 26, and a similar card case 27 is preferably formed on the front face of the middle portion of the front flap 16 but 90 said card cases 25, 26 and 27 are not essential as far as the invention is concerned.

It will be noticed that the front flap 15 can be readily swung into a completely open position, as indicated in Fig. 2, for the insertion or removal of a pile of bills, the bottom one of which overlies the back 10, and the sides of the bill being tucked under the side pieces 11 and 12. The front flap 15 can then be readily swung over onto the upper- 105 most bill and the end portions 17 and 18 tucked under the side pieces 11 and 12 and

engaged while doing so with the loops 21 thereof, if desired. The end portions of the bill book can now be readily folded one on top of the other with the innermost portion 5 overlying the middle portion of the front flap 15, as plainly indicated in Fig. 3.

It will be noticed that by spacing the connection 16 from the inner edges of the side pieces 11 and 12, the end portions of the 10 billbook with the bills therein can be readily folded one on top of the other without producing a bulky package even if a very large number of bills are placed in position in the bill book.

15 It is further understood that the free end portions 17 and 18 of the front flap 15 readily accommodate themselves to curved shape when folding the end portions of the bill book one upon the other, as previously explained, especially as the said end portions 20 17 and 18 are free to slide under the side pieces 11 and 12 when folding or unfolding the bill book, but the free end portions 17 and 18 are held against being accidentally 25 pulled out from under the side pieces 11 and 12.

Having thus described my invention, I claim as new and desire to secure by Letters Patent:—

30 1. A bill fold, comprising a flexible back approximately of the size of a bill, side pieces overlying the side portions of the said back and connected thereto along the outer and bottom edges, and a closing flap connected at the middle portion of the bottom edge with the corresponding portion of the bottom edge of the said back, the 35 ends of the connected middle portion of the said closing flap being spaced from the adjacent inner edges of the said side pieces, the free end portions of the said closing flap being adapted to be tucked under the said side pieces, the latter being adapted to be folded one on the other, the innermost over- 40 45

lying the middle portion of the said closing flap.

2. A bill fold, comprising a flexible back approximately of the size of a bill, side pieces overlying the side portions of the said back and connected thereto along the outer and bottom edges, a closing flap connected at the middle portion of the bottom edge with the corresponding portion of the bottom edge of the said back, the ends of the connected middle portion of the said closing flap being spaced from the adjacent inner edges of the said side pieces, the free end portions of the said closing flap being adapted to be tucked under the said side pieces, the latter being adapted to be folded one on the other, the innermost overlying the middle portion of the said closing flap, and retaining loops extending from top to bottom on the inner faces of the said side pieces adjacent the inner edges thereof to receive and hold the free end portions of the said closing flap. 50 55 60 65

3. A bill fold, comprising a flexible back approximately of the size of a bill, side pieces overlying the side portions of the said back and connected thereto along the outer and bottom edges, and a closing flap connected at the middle portion of the bottom edge with the corresponding portion of the bottom edge of the said back, the 70 ends of the connected middle portion of the said closing flap being spaced from the adjacent inner edges of the said side pieces, the free end portions of the said closing flap being adapted to be tucked under the said 75 side pieces, the latter being adapted to be folded one on the other, the innermost overlying the middle portion of the said closing flap, and means to limit the sliding out movement of the free end portions from 80 85 under the said side pieces.

JAMES MACDONALD.
